(57) **CLAIM**

The ornamental design for a multi-lap connector for a supported structure, substantially as shown and described.

DESCRIPTION

FIG. 1 is a top isometric view of a multi-lap connector for a supported structure, showing my design;
FIG. 2 is a top perspective view thereof;
FIG. 3 is a left side view thereof;
FIG. 4 is a right side view thereof;
FIG. 5 is a left side rotational view thereof;
FIG. 6 is a right side rotational view thereof;
FIG. 7 is a front view thereof;
FIG. 8 is a rear view thereof;
FIG. 9 is a top view thereof;
FIG. 10 is a bottom view thereof; and,
FIG. 11 is a bottom isometric view thereof.
